HERNIA SUPPORT

Application filed October 15, 1927. Serial No. 226,293.

This invention relates to hernia supports and my improvements are directed to a device of this character which is highly efficient, self adjusting, and extremely comfortable in use.

In describing this new hernia support it is unnecessary to enter into any extensive discussion of hernia, its causes, development and treatment, but sufficient to remember that the muscles forming the abdominal wall are all broad flat muscles, one overlapping and reinforcing the other. At certain places between the muscle layers, there are narrow slitlike openings for the passage of the spermatic cord, the round ligament, etc. As long as the muscles retain their normal strength and the abdominal inside pressure remains normal, this anatomical arrangement works well; but once the muscles weaken and give way, the abdominal content at once begins to force its way through the opening and a hernia is established.

To remedy this condition and counteract it by means of an external support or truss, the plain indication is to imitate and reinforce the natural anatomical arrangement. To do this effectively is, however, no easy matter. The support must be flat and broad like the muscles themselves and lay in close opposition not only to the abdominal wall but to the circumference of the lower pelvis as well. If it fails to do this however slightly the hernia is apt to escape. At the same time the support must be held in position against the abdominal wall with a pressure both even and sufficiently firm. This pressure, however, may be comparatively light or practically unnoticeable.

My improved support is made preferably of sheet celluloid and shaped exactly to conform to the contour of the lower abdomen, its side lines fitting into the groove formed by the lower portion of Poupart's ligament, its lower edge paralleling the upper and anterior border of the pubic bone but extending a little below its crest and overlapping it. The upper edge of the support extends across the abdomen from a point midway between the superior and inferior spinous processes of the ileum forming a slight upward curve.

To give it a certain amount of thickness or depth, the celluloid sheeting is bent and formed into triangular shaped tapered columns, placed side by side and pointing to an imaginary center below, and held together and in position by wire (or other means) and resting on that part of the celluloid sheet intended for contact with the abdominal wall.

The size or depth of the columns may vary so as to assist in giving the required pressure in each individual case, this pressure being produced by a belt, (elastic or not) which is girthed around the hips, like the belt worn by sailors, in a position partly over or right above the great trochanters. The belt crosses the support, to which it is attached, by its lower edge at the middle point of the lowest part of the columns.

This support is firm and rigid except transversely. The arrangement of the columns and their attachment to one another allow a slight separation of their forward edges, thus making possible by the action of the belt a slight flexure of the support transversely, this flexure being sufficient to cause the support to shape itself closely to the contour of the abdominal wall and hold the wall in the position intended by nature. The hernia thereby is closed and in a position devoid of all strain, allowing the muscles relieved from the hernial and pain strain to act normally, making it possible for the muscles to be used and trained up to their normal strength. This may mean a cure provided the severity of the condition, the age or individual health do not render such a result impossible.

The part of the support resting against the abdomen may be perforated or not. The support stays in place without any groin straps but these can of course be used. That the support must have a certain thickness or depth is necessitated by the prominence of the anterior portion of the ileum over which the belt passes; this thickness or depth also assists in regulating the pressure. Both inguinal canals being covered by the support, there is no necessity for specifying or measuring for right or left hernial support; it supports both sides.

Other features and advantages of my invention will hereinafter appear.

In the drawings:

Figure 1 is a perspective elevation of my improved hernia support, as in use.

Fig. 2 is a top plan view of said support.

Fig. 3 is a side sectional view thereof, and

Fig. 4 is a partial front sectional view of the same.

10 The support which is the subject of this application is composed of thin sheet material, such for example as celluloid, which is folded upon itself to provide a cellular formation, arcuate in contour, adapted to 15 fit over the lower abdomen, said formation having side edges that are inclined to fit in the grooves lying between the abdomen and legs of the user.

In producing this support I cut a circular 20 strip out of a sheet of celluloid or the like and fold said strip upon itself to provide the inner, arcuate portion 1 which is intended to lie contactingly against the abdomen. The folds of the strip at the opposite sides of portion 1, indicated at 2, 2 are such as to provide 25 converging rounded edges, adapted to fit conformingly within the crevices between the abdomen and legs of the wearer. The strip material thus folded provides side walls 3, 3 30 whose depth determines the thickness of the pad constituting the support, the strip material being folded back again, inside the walls 3, 3, in the formation of inner walls 4, 4. The opposite end portions of the strip material are, from said inner walls 4, 4, respectively folded to form series of hollow, 35 tapered columns that are each triangular in cross-section, succeeding columns having respectively the inner bases 5 and outer bases 40 6, and being divided by the walls 7. The inner bases 5 all lie against the strip portion 1, while the bases 6 are all in an arc that is parallel with said inner bases 5 and portion 1.

The hollow columns thus described are 45 tied together by means of wires 8 or other connectors to thereby fabricate said columns into a cellular pad, and the free ends 9, 9 of the strip, which are caused to meet at about the centre of the pad, are folded over so that 50 said free ends may also be engaged by the tying means referred to.

The inner portion 1 of the pad extends 55 above and below the hollow columns and is curved outwardly at both its upper and lower edges, to thereby present curved, smooth surfaces for contact with the abdomen and prevent the discomfort that would arise if sharp edges of said portion were presented to the flesh.

60 The support is localized in its effective position upon the lower abdomen by means of a belt 10 that extends transversely across the support, at its outer surface, and is adapted to encircle and fasten about the waist of the 65 wearer. Said belt may be attached to the

support as at 11, and may pass through guides 12 provided at the sides of said support.

By reason of the thickness of the support, and the pressure of the belt being applied to its outer surface, thereby said support is caused to bear against the lower abdomen, over the affected region, with a degree of pressure serving to ameliorate the hernial condition.

70 The linkage or tying together of the hollow columns accords a degree of stiffness to the pad which enables it to constitute an efficient support whilst also creating an articulation that permits sufficient flexure to accommodate the pad to the body movements.

75 Variations within the spirit and scope of my invention are equally comprehended in the foregoing disclosure:

I claim:

1. A hernia support composed of thin, flexible sheet material folded into a series of hollow tapering columns, triangular in cross-section and connected in articulation, sheet inner surfacing for said columns, and means 80 for holding said support against the lower abdomen.

2. A supporting pad composed of sheet celluloid formed into vertically disposed folds and a surface strip at one side of the folds, 85 in pad formation.

3. A supporting pad composed of sheet celluloid formed into vertically disposed folds and a surface strip at one side of the folds, in pad formation, said pad having curved upper and lower edges, downwardly converging side edges and being concavo-convex in 90 transverse contour.
